BORING TOOL

Russell B. Wiseman, Costa Mesa, Calif.
(2395 Tustin Ave., Newport Beach, Calif.)

Filed Sept. 21, 1961, Ser. No. 66,783

Term of patent 14 years

(Cl. D54—4)

FIG 1

FIG 2

FIG 3

FIG 5

FIG 4

FIG 6

FIGURE 1 is a side elevational view of a boring tool showing my new design;

FIGURE 2 is a fragmentary perspective view thereof;

FIGURE 3 is an end view thereof on an enlarged scale;

FIGURE 4 is a cross-sectional view thereof taken on the line 4-4 of FIGURE 1;

FIGURE 5 is a view similar to FIGURE 2 but showing a modified form of the present invention; and

FIGURE 6 is a view similar to FIGURES 2 and 5 but showing still a further modification of the present invention.

The cutting end of the tool, as shown at the right of FIGURE 1, has an opposite face that is substantially flat and similar to the side shown, the blade being relatively thin in cross section.

In FIGURES 1, 2, 5 and 6, the opposite sides are substantially mirror images of the sides shown.

The design is characterized by the configuration of the butt and butt-shank merging portions, wherein the butt possesses four relatively wide flat faces interposed

between four thin curved faces which each lie on the periphery of a common cylinder, and at least some of the flat faces merge with the tapered shank in a manner producing V-shaped extensions.

This application is a continuation-in-part of my earlier filed application Serial No. D. 63,017, filed November 29, 1960, now abandoned.

I claim:

The ornamental design for a boring tool, as shown and described.
